PENDANT OR OTHER ARTICLE OF JEWELRY

Albert J. Roth, 1901 Main St.,
Newington, Conn. 06111

Filed Nov. 29, 1967, Ser. No. 9,584

Term of patent 14 years

(Cl. D45—17)

Fig. 1.

Fig. 2.

FIG. 1 is a front view of a pendant or other article of jewelry showing my novel design; and

FIG. 2 is an edge view thereof.

The rear of the design is substantially identical to the front view in FIG. 1.

I claim:

The ornamental design for a pendant or other article of jewelry, substantially as shown and described.
